CLAIM

The ornamental design for a forefoot pulse device, as shown and described.

DESCRIPTION

FIG. 1 is a perspective view of a forefoot pulse device; FIG. 2 is a perspective view thereof; FIG. 3 is a front elevation view thereof; FIG. 4 is a rear elevation view thereof; FIG. 5 is a right-side elevation view thereof; FIG. 6 is a top plan view thereof; FIG. 7 is a cross-sectional elevation view of the forefoot pulse device of FIG. 6, taken in the direction of 7-7'; FIG. 8 is a cross-sectional perspective view, thereof, taken in the direction of 8-8'; and, FIG. 9 is a cross-sectional view thereof, taken in the direction of 7-7', shown in a condition of use for clarity of disclosure.

The equal-length broken lines on the forefoot pulse device depict unclaimed portions thereof, and form no part of the claimed design. The equal-length broken lines showing a human foot in FIG. 9 depict environmental structure and form no part of the claimed design. All broken lines form no part of the claimed design.

1 Claim, 6 Drawing Sheets
